(57) **CLAIM**

We claim the ornamental design for a sewing needle, as shown and described.

DESCRIPTION

FIG. 1 is a perspective view of a sewing needle showing our new design;

FIG. 2 is a left side elevation view thereof;

FIG. 3 is a right side elevation view thereof;

FIG. 4 is a bottom elevation view thereof;

FIG. 5 is a top elevation view thereof;

FIG. 6 is a rear elevation view thereof; and,

FIG. 7 is a front elevation view thereof.

The needle is shown broken away to indicate indeterminate length.
